SPARK PLUG

Filed Feb. 1, 1926

Inventor:
George W. Gardner.
By Chas. A. Dunn
Atty.

UNITED STATES PATENT OFFICE.

GEORGE W. GARDNER, OF FLINT, MICHIGAN.

SPARK PLUG.

Application filed February 1, 1926. Serial No. 85,177.

This invention has relation to spark plugs for internal combustion engines, and more particularly to the formation and construction of the points or electrodes thereof.

5 The main object of the invention, is the provision of a spark plug which shall be quite simple and inexpensive to manufacture, or repair, should any of its parts become broken or injured, easy of assemblage 10 and application, as well as, of such construction, arrangement and formation of certain of its parts, as to afford a more highly efficient device of this character or class, than has heretofore been in common or general 15 use, especially, with regard to the characteristics of the sparks produced and the cleanliness of the points or electrodes, or the prevention or elimination of carbon thereon or therefrom.

20 More specifically speaking, the invention contemplates as another of its objects, a spark plug in which the primary and secondary electrodes or points thereof, each has its adjacent end to the other electrode split, 25 or provided with a reversed substantially V-shaped recess in register with one another, thereby forming a substantially diamond shaped opening between the adjacent ends of the electrodes for increasing their sparking 30 capacity and causing the electric current to spread and jump all through the split portions of the electrodes.

The invention also has as one of its features, the provision of the adjacent walls of 35 said recesses each with an edge formed substantially, knife edged in shape, whereby the current will be caused to be condensed in its act of jumping or passing from the side walls of one of the recesses to the other side 40 walls of the same recess, and from thence through the adjacent faces of the split electrodes, which faces are spaced the required distance apart and provide the requisite 45 sparking gap between them. Also, this formation of the walls of each recess serves to make them self-cleaning, or reduces to a 50 minimum the accumulation of carbon or oil at the tips or adjacent faces of the electrodes, thereby causing them to effect a stronger, more positive or certain sparking 55 action.

Other objects and advantages of the invention will become apparent from the following description and explanation.

55 The invention consists in certain peculiarities, of the construction, novel combina-

tion and arrangement of the various parts thereof, as will be hereinafter more fully set forth and specifically claimed.

In the accompanying drawing, which 60 serves to illustrate an embodiment of the invention:

Figure 1 is a view in elevation of a spark plug embodying my invention showing the parts thereof in about the positions they will 65 occupy when the device is ready for use.

Figure 2 is a view partly in section and partly in elevation, showing the sides of the electrodes, and

Figure 3 is a similar view, but showing 70 face views of parts of the electrodes.

Similar numerals of reference designate like parts throughout the different views of the drawing.

The spark plug is shown in the present 75 instance, of the separable type for the convenience of repairing the same, but it will be understood that the illustration is for the purpose of exemplification only, and that other types, or the standard makes, may be 80 employed; without a departure from the spirit of my invention, so long as they employ electrodes of the construction covered by the appended claim.

By reference to the drawing, it will be 85 understood that the spark plug is made up of a centrally hollow plug 4, which has its lower portion screw threaded as at 5, to engage an opening in the cylinder of an 90 internal combustion engine, and its upper portion formed with an angular head 6, which can be engaged by a wrench used for attaching said plug in place, and a porcelain, or an insulator core 7, having a central bore extended longitudinally therethrough. The 95 member 7, is fitted in the hollow of the plug 4, and held in place by means of a surrounding nut 8, engaging the screw threaded portion of the upper part of said plug.

Extended through the bore of the core 7, 100 is the primary electrode 9, the lower end of which projects slightly beyond the lower extremity of the member 4, as shown, and has said end split as will be presently explained. The upper end of the electrode 9, extends 105 through the upper end of the core 7, and has thereon a nut 10, used for fastening it to one of the current wires of an ignition system (not shown).

Fixed in a suitable opening in the lower 110 edge of the member 4, is the upper end of the secondary electrode 11, the opposite portion

of which is curved inwardly and upwardly so that its said vertical part aligns with the lower portion of the primary electrode. As shown, the adjacent extremity of each of the 5 electrodes is split, or provided each with a pair of diverging prongs 12, and 13, which are spaced apart, but with their tip ends in registry with one another to provide the requisite sparking gap. The tips or faces of 10 the ends of the prongs are preferably flat and the inner surface of each of the prongs 12, and 13, are usually of a knife-edge structure, as shown.

It is apparent that by employing a spark 15 plug embodying my improvements, the points of the electrodes can be formed by the use of suitable dies, are preferably made of basic wire of suitable size, and that the 20 sparking efficiency of the plug will be increased, more reliable and the sparks stronger or more intense in heat.

It is further obvious, that by reason of

the divergency of the prongs 12, and 13, or rather, by reason of the divergency of the inner surfaces of each pair of said prongs, 25 and by reason of the fact that the end of each electrode is split, the inner surfaces will be shielded by the outer portions of each split or recess, as well as the tips and thus prevent the accumulation of foreign 30 matter thereon.

Having thus fully described the invention, what I claim as new and desire to secure by Letters Patent is;

In a spark plug, the combination with a 35 plug having means to secure it to a cylinder of an engine, of primary and secondary electrodes mounted thereon and having one of their ends in juxtaposition and substantial alignment with each other, each of said 40 adjacent ends of said electrodes having a pair of divergent prongs having their portions adjacent their tips reduced.

GEORGE W. GARDNER.
